UNITED STATES PATENT OFFICE.

JOSIAH TISDALE, OF NORWOOD, MASSACHUSETTS.

NEEDLE-HOLDER FOR SEWING-MACHINES.

SPECIFICATION forming part of Letters Patent No. 244,500, dated July 19, 1881.

Application filed April 18, 1881. (Model.)

To all whom it may concern:

Be it known that I, JOSIAH TISDALE, a citizen of the United States, residing at Norwood, in the county of Norfolk and State of Massachusetts, have invented certain Improvements 5 in Self-Setting Needle-Holders for Sewing-Machines, of which the following is a full, clear, and exact description, reference being had to the accompanying drawings, making part of 10 this specification, in which—

Figure 1 is an elevation (enlarged) of a portion of the needle-bar of a sewing-machine having my improved needle-holder applied thereto. Fig. 2 is a vertical section through the same. 15 Fig. 3 is a horizontal section on the line xx of Fig. 2. Fig. 4 is a perspective view (enlarged) of my improved needle-holder detached, with the needles in place therein.

My invention relates to an improvement in 20 needle-holders for sewing-machines of that class in which two needles are attached to and operated by the needle-bar, so as to sew two seams at once.

In needle-holders of this description as heretofore constructed, where the two needles are 25 held in grooves upon opposite sides of the needle-bar by a collar or clamp provided with a single set-screw, considerable difficulty and delay have been experienced in setting or adjusting the needles, for the reason that this 30 operation was necessarily performed while they were in a vertical position upon the needle-bar, and when the clamping device was loosened one needle was liable to drop out or slip down 35 out of place while the other was being set.

My invention has for its object to overcome 40 this difficulty and enable the needles to be readily set or adjusted in their proper relative positions before being applied to the needle-bar; and it consists in a removable needle-holder 45 of peculiar construction, in which the needles are temporarily held when it is removed from the needle-bar, with sufficient force to keep them in place, by a spring pressure-plate, which admits of their being set or adjusted without 50 liability of slipping out of place, the pressure-plate being afterward forced against the needles to hold them securely in place on the 55

needle-bar by the same set-screw which confines the holder upon the lower end thereof. 50

In the said drawings, A represents a needle-bar, which may be of any suitable pattern and adapted to fit any ordinary machine.

B is the removable needle-holder, which is made in the form of a collar, and is secured to the lower end of the needle bar by means of a set-screw, *a*, with its upper surface in contact with the shoulder 5 of the needle-bar. Within this holder or collar B is fitted a pressure-plate, *b*, which is held in place by a pin, *c*, the end of which is riveted thereto, this pin, which extends through the side of the collar, being turned down to form a shoulder, *d*, between which and the shoulder *e* of the recess or aperture 10 in which the pin slides is placed a short 60 spiral spring, *f*, which thus serves to draw the plate toward the side *g* of the collar B with sufficient force to automatically hold the two needles *h* in place within the holder, as seen in Fig. 4, the needles being inserted between 65 the pressure-plate *b* and the side of the holder in suitable grooves, *k l*, formed opposite each other in the plate and holder, whereby the needles are kept parallel at the proper distance apart and their verticality insured. When the 70 holder B is removed from the needle-bar the pressure-plate *b* bears with sufficient force upon the needles to hold each of them securely in place independently of the other, and at the same time admit of their being easily slid up 75 or down to set or adjust them as required, which operation is thus greatly facilitated, as it can be performed when the holder is removed from the machine, and all liability of one needle slipping out of place while the other is being 80 adjusted is entirely avoided. After the needles have been adjusted in the holder B the latter is slipped onto the lower end of the needle-bar 85 A and secured firmly in place by means of the set-screw *a*, which also presses the needle-bar 90 against the plate *b* and simultaneously clamps the two needles immovably in place, the single set-screw thus serving as a means of both holding the needles within the holder and the holder to the needle-bar, the upper ends of the needles 95 when in place resting against the shoulder 5

of the needle-bar, which thus serves as a gage to determine their height. When the clamping-screw *a* is loosened the holder *B* and the needles which it contains can be instantly removed without any liability of the needles dropping out, as heretofore, which will be found to be a great convenience.

It is obvious that a needle-holder constructed in accordance with my invention may be adapted to hold three or more needles, if desired, or it may be used to hold a single needle only, if required.

What I claim as my invention, and desire to secure by Letters Patent, is—

15 1. In a needle-holder for sewing-machines, the combination, with the collar *B*, of a spring pressure-plate adapted to automatically confine the needles in place within the collar when the latter is removed from the needle-bar, and at the same time allow the needles to be set or adjusted independently of each other without liability of dropping or slipping out of place, substantially as described.

2. The combination, with the collar or holder *B*, of the spring pressure-plate *b*, adapted to automatically retain a series of two or more

needles within the holder when the latter is removed from the needle-bar and admit of their ready adjustment, and the set-screw *a*, arranged to simultaneously clamp the holder upon the needle-bar and the needles between the plate *b* and the holder, substantially as and for the purpose set forth.

3. The combination, with the needle-bar *A*, of the holder *B*, with its set-screw *a* and spring *b*, pressure-plate *b*, adapted to hold the needles in suitable grooves and be forced against them to clamp them in place by the same set-screw which confines the holder upon the lower end of the needle-bar, substantially as described.

4. The combination of the collar or holder *B*, the pressure-plate *b*, secured to the sliding pin *c*, and the spring *f*, placed within the recess 10, all arranged to operate substantially in the manner and for the purpose set forth.

Witness my hand this 13th day of April, 45
A. D. 1881.

JOSIAH TISDALE.
